UNITED STATES PATENT OFFICE.

PETER T. COFFIELD, OF DAYTON, OHIO, ASSIGNOR TO THE COFFIELD MOTOR WASHER COMPANY, OF DAYTON, OHIO.

DRAIN-SPIGOT.

1,098,712.

Specification of Letters Patent.

Patented June 2, 1914.

Application filed January 7, 1914. Serial No. 810,739.

To all whom it may concern:

Be it known that I, PETER T. COFFIELD, a citizen of the United States, residing at Dayton, in the county of Montgomery and State 5 of Ohio, have invented certain new and useful Improvements in Drain-Spigots; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 This invention relates to new and useful improvements in drain spigots.

The invention relates to a spigot especially designed for wash tubs, but it is equally as useful in controlling the drainage opening in other vessels.

20 The object of the invention is to provide a simple and convenient drain spigot the parts of which cannot become separated. The ordinary drain plug for controlling 25 the drain opening of a wash tub may be entirely withdrawn from the opening and, as a consequence, the exit of the water is not controlled but is allowed to splash out much to the annoyance of the person 30 having charge of the laundry work, besides the frequent misplacing of the plug. The present improvement avoids these objections by providing means whereby the plug cannot be wholly withdrawn from the drain 35 opening and the drainage of the water is so controlled that splashing is prevented.

Referring to the accompanying drawings, Figure 1 is a side elevation of a wash tub equipped with my invention; Fig. 2 is a 40 vertical longitudinal section through the spigot showing the same closed; Fig. 3 is a view similar to Fig. 2 showing the spigot open; Fig. 4 is a section on the line *a—a* of Fig. 3; and Fig. 5 is a cross-section of the 45 plug on the line *b—b* of Fig. 2.

In the specification and drawings, similar reference characters indicate corresponding parts.

Referring more particularly to said drawings, 1 represents a cylindrical shell provided with ears 2 having screw openings 3 by means of which said shell may be attached to any well known form of tub 13. The tub 13 is provided with the usual drainage 50 opening which receives the nipple 4 of the

spigot. The outer surface of said nipple is tapered to provide a wedge-like engagement with the opening and, likewise, the bore of said nipple is tapered as at 5 to provide for a suitable engagement of the tapered end 10 of the plug 8. The shell 1 is provided with a vertically and downwardly projecting nozzle or bib 6 which communicates with the interior of the tube 13 through the bore 5 and through which the water is drained from the tub. The plug extends out of the shell through an opening 7 and terminates in a hand portion 9. The body of the plug 8 or that portion lying within the shell 1 is provided with a circumferential groove 12 for the reception of an elastic collar of flange 11, preferably rubber. This flange 11 is placed on the plug at a point sufficiently removed from the tapered end so as to not interfere with the proper insertion of said plug in the opening 5 when it is desired to close said opening. The function or purpose of the collar or flange 11 is two-fold, to-wit, it prevents the plug 8 being wholly withdrawn from the shell by engaging the wall surrounding the opening 7 and it acts as a packing to seal said opening 7 and thereby prevents any leakage at that point when the tub is emptying. The peripheral shoulders formed by the groove 12 prevent the said collar becoming dislodged from its position and provides a simple and convenient way of mounting said collar in the plug. The parts are easily united or assembled by holding the collar 90 on the interior of the shell in the path of the plug when the latter is inserted in the opening 7. The tapered end 10 of the plug expands said collar until the groove 12 is reached at which time the said collar contracts into said groove. It is apparent that a spigot thus constructed will obviate the disadvantages heretofore experienced with the prior means for controlling the drainage 95 of wash tubs.

Having described my invention, I claim.

1. In a device of the type specified the combination with a shell adapted to be inserted in the drainage opening of a liquid-containing receptacle and provided with an angularly disposed outlet opening communicating with said receptacle, of a plug mounted in said shell and controlling said opening, and means carried upon said plug for preventing the withdrawal of the 110

plug from said shell in the manipulation of the plug.

2. In a device of the type specified, the combination with a shell having an angularly disposed drain-passage through it and an extended portion terminating in a flanged opening, of a plug mounted in said shell and extending through said flanged opening and controlling said drain-passage, said plug having a groove in its circumference, and an elastic collar mounted in said groove and adapted to limit the withdrawal movement of the plug and to seal the flanged opening through which the plug projects.

3. In a device of the type specified, the combination with a shell having a tapered

nozzle providing an inlet opening, a flanged opening in alignment with said nozzle opening, and a nozzle arranged between said first named openings and providing an outlet from said shell, of a plug supported in said flanged opening and controlling the passage through said nozzles, and an elastic collar fixed to the body of said plug and adapted to engage the flange surrounding the plug-supporting opening to limit the withdrawal movement of said plug.

In testimony whereof I affix my signature, in presence of two witnesses.

PETER T. COFFIELD.
